CLAIM

The ornamental design for a football bottle, as shown and described.

DESCRIPTION

FIG. 1 is a front view of my design for a football bottle.

FIG. 2 is a right side view thereof.

FIG. 3 is a left side view thereof.

FIG. 4 is a rear view thereof.

FIG. 5 is a top plan view thereof; and,

FIG. 6 is a bottom plan view thereof.

The top and bottom of the bottle shown in broken lines illustrates that portion of the article in which the design is embodied that forms no part of the claim.
